Primary Examiner — Catheri Oliver-Garcia(74) Attorney, Agent, or Firm — Benjamin M. Hanrahan; Hanrahan Law Firm, P.A.(57) CLAIM

The ornamental design for a waistband pack with a two-way zippered pocket, as shown and described.

DESCRIPTION

FIG. 1 is a top perspective view illustrating my design for a waistband pack with a two-way zippered pocket with the ends thereof engaged.

FIG. 2 is a front perspective view thereof with the ends disengaged.

FIG. 3 is a front view thereof.

FIG. 4 is a rear view thereof.

FIG. 5 is a top view thereof.

FIG. 6 is a bottom view thereof.

FIG. 7 is a left side view thereof; and,

FIG. 8 is a right side view thereof.

The pack is shown broken away to indicate indeterminate length.

1 Claim, 4 Drawing Sheets(56)
